UNITED STATES PATENT OFFICE

2,457,513

INTERNAL-COMBUSTION HOT-AIR HEATER

Lynn A. Williams, Jr., Northfield, Ill., assignor to
Stewart-Warner Corporation, Chicago, Ill., a
corporation of Virginia

Application February 26, 1943, Serial No. 477,191

3 Claims. (Cl. 126—116)

1

My invention relates to heaters and more particularly to heaters of the internal combustion type.

In heaters of the internal combustion type, it is common to have products of combustion pass directly from a combustion chamber into one end of a heat exchanger over which ventilating air is directed. That portion of the heat exchanger which is first contacted by the hot gases issuing from the combustion chamber is heated to a much higher temperature than is the remainder of the heat exchanger, with the result that this portion of the heat exchanger is sometimes burned out or temperature stresses and strains are set up in the heat exchanger which shorten its life and impair its efficiency. An object of my invention is to overcome these disadvantages of the prior art heaters.

Another object of my invention is to vary the rate of heat transfer between the hot products of combustion and the walls confining these gases by varying the velocity of flow of these gases in different parts of the heater.

Another object of my invention is to vary the rate of heat transfer between walls heated by the hot gases of combustion and ventilating air directed over these walls by varying the velocity of flow of the ventilating air in different parts of the heater.

Another object of my invention is to vary the velocities of flow of fluids passing through the heater in different portions of the heater to provide a more uniform heating of the metal parts of the heater.

Another object of my invention is to provide a heater wherein walls separating the hot products of combustion from the ventilating air are maintained at substantially uniform temperature throughout the heater.

Another object of my invention is to provide a heater wherein hot products of combustion and ventilating air flow in opposite directions and wherein a substantially uniform rate of heat transfer from the products of combustion to the ventilating air is maintained throughout the entire heater.

Other objects and advantages will become apparent as the description proceeds.

In the drawings:

2

Fig. 1 is a longitudinal, sectional view of a heater embodying my invention;

Fig. 2 is a transverse, sectional view taken on the line 2—2 of Fig. 1; and

Fig. 3 is an end elevation looking from the left in Fig. 1.

The heater shown in Figs. 1, 2 and 3 has a generally cylindrical casing 10 provided with a tapered inlet end 12 adapted to be connected to 10 a ram, blower, or other suitable source of air supply. Part of the air entering the inlet 12 flows lengthwise through a tube 14 and enters the tapered inlet 16 of a pipe 18 leading to a carburetor 20. The carburetor is provided with 15 the usual float bowl 22 connected by pipe 24 to any suitable source of fuel supply. The float bowl 22 furnishes fuel to a jet 26 located in the throat of the Venturi tube 28 which delivers a mixture of fuel and air to an induction tube 30.

The induction tube 30 is preferably of uniform diameter and extends through the casing 10 and outer wall 32 of a combustion chamber 34 formed between the cylindrical sheet metal outer wall 32 and a cylindrical sheet metal inner wall 36. The induction tube 30 has a preheating portion 38 which lies within the combustion chamber 34 and is curved about the axis thereof. This induction tube terminates in an outlet end 40 positioned to discharge combustible mixture 25 tangentially to the annular combustion chamber 30 to create a ring of flame therein, as described and claimed in the co-pending application of 35 Henry J. DeN. McCollum, Serial No. 477,080, filed February 25, 1943, now Patent No. 2,433,618 is- 30 sued December 30, 1947.

The fuel and air mixture delivered to the combustion chamber by the induction tube 30 is ignited by an electrical igniter 42 (Fig. 3). The hot gases resulting from the combustion in the 40 combustion chamber, pass from the righthand end of this chamber into a tapered annular passage 44 formed between tapered sheet metal walls 46 and 48 which constitute extensions of combustion chamber walls 32 and 36, respectively. 45 As the hot gases flow lengthwise of the tapered passage 44, they are mixed with secondary air entering this passage by way of a circular series of openings 50, preferably formed by displacing tongues 52 and arranging these tongues at such 50 an angle that the secondary air entering the

passage 44 is traveling in the same general direction as the gases therein.

As the hot gases travel lengthwise of the passage 44, these gases give up their heat to the walls 46 and 48 thereof. Because the cross-section of the passage 44 decreases toward the outlet 54 through which the cooled gases are discharged to atmosphere, the velocity of flow of the gases continually increases as these gases approach this outlet. The rate of heat transfer between these gases and the walls 46 and 48 tends to increase with the increased velocity of flow of these gases, as they approach the outlet 54, but this is offset somewhat by the cooling of these gases as they travel lengthwise of the passage 44.

The heat transferred from the hot gases of combustion to the wall 46 and combustion chamber wall 32 are absorbed by the ventilating air flowing through an annular passage 56 formed between these walls and the casing 10. The tapered wall 46 causes the cross-section of this passage 56 to decrease from right to left so that the ventilating air flowing through this passage is flowing at a faster velocity as it approaches the lefthand end of the passage and tends to absorb more heat from the lefthand end of the wall 46. The reverse tapering of the gas passage 44 and of the ventilating air passage 56 on opposite sides of the wall 46 are designed to maintain this wall at substantially uniform temperature throughout its length to prevent overheating of any particular portion of this wall, to prevent the creation of temperature strains and stresses therein and to provide maximum efficiency of operation of the heater.

The heat absorbed by the tapered wall 48 and inner wall 36 of the combustion chamber is absorbed by ventilating air flowing through the annular passage 58 formed between these walls and the tube 14. This passage 58 decreases in cross-section from right to left, as viewed in Fig. 1, so that the velocity of air flow therethrough progressively increases despite the diversion of a small amount of secondary air through the openings 50 and into the gas passage 44. The differing velocities of flow of the hot gases on one side of the tapered wall 48 and of the ventilating air on the opposite side thereof serve to maintain this wall at substantially uniform temperatures throughout and thus prevent excessive heating of any portion of this wall, prevent the formation of undue temperature stresses and strains therein, and promote maximum heat transfer through this wall.

The righthand ends of the ventilating air passages 56 and 58 are in open communication with the air inlet 12 and the lefthand ends of these passages discharge into the lefthand end of the casing 10. This end of the casing may direct the ventilating air into an airplane cabin or other space to be heated or into a duct system having selected outlets located in the same or different spaces.

The combustion air flowing to the carburetor 20 through the tube 14 absorbs heat from the walls of this tube to facilitate vaporization of the fuel mixed with this air. Additional preheating of the combustible mixture is provided by the curved portion 38 of the induction tube 30 which is made of the appropriate length to insure the desired preheating of the mixture. The length of this portion 38 will, of course, vary, being shorter for light fuel such as gasoline, and longer for heavy fuels such as kerosene or fuel oil.

From the foregoing description it will be ap-

parent that the velocity of flow of the products of combustion increases as these products move farther and farther away from the combustion chamber, whereas the ventilating air travels faster and faster as it approaches the combustion chamber and these varying velocities of gas and air flow are utilized to improve the efficiency of the heater and to eliminate temperature stresses and strains and burn out portions. These advantages are accomplished by a simple structure which is light in weight and which may be easily and economically manufactured of conventional materials to produce a compact heater having a high heat output and capable of use with light or heavy fuels.

While I have illustrated and described a single embodiment of my invention, my invention is not limited to the details shown and described, but may assume numerous other forms and the scope of my invention is defined in the following claims.

I claim:

1. A heater of the class described, comprising a cylindrical casing having one end adapted to be connected to a source of air supply, a frustoconical wall in said casing and cooperating therewith to form a tapered ventilating air passage communicating with said source, a second frustoconical wall in said first-mentioned wall and cooperating therewith to form a gas passage tapered oppositely to said ventilating air passage, a tube in said second-mentioned wall and cooperating therewith to form a ventilating air passage tapered in the same direction as said first-mentioned air passage, a carburetor receiving a supply of combustible air from said tube, means forming a combustion chamber communicating with said tapered gas passage, and an induction tube connecting said carburetor with said combustion chamber.
2. A heater of the class described comprising a tubular casing having one end connected to a source of air supply, a tapered tubular wall coaxially disposed in said casing and cooperating therewith to form a ventilating air passage communicating with said source and tapering continuously therefrom, a second tubular wall coaxially disposed within said first-mentioned wall and tapered in the opposite direction to form a gas passage tapered oppositely to said ventilating air passage, an additional tubular member coaxially disposed within said second tubular wall and cooperating therewith to form a second ventilating air passage tapered in the same direction as said first-mentioned air passage and also communicating with said source, and means forming a combustion chamber communicating with the larger end of the tapered gas passage.
3. A heater of the class described comprising means forming a combustion chamber, heat exchange means receiving hot products of combustion from said combustion chamber, and means for directing ventilating air over said heat exchange means toward the combustion chamber, said combustion chamber forming means and said heat exchange means consisting of walls forming a single relatively long passageway for conveying the products of combustion, said passageway tapering continuously with increased distance from said combustion chamber to cause the products of combustion to flow therethrough with accelerating velocity, and said ventilating air directing means comprising a shell concentric with said passageway and forming with one of said passageway forming walls a ventilating air conduit decreasing continuously in cross sec-

tional area as it approaches the combustion chamber for causing the ventilating air to flow with continuously increasing velocity toward said combustion chamber.
